UNITED STATES PATENT OFFICE.

MAX SCHALSCHA, OF SUMMIT, NEW JERSEY, ASSIGNOR TO UNION IRON WORKS, OF HOBOKEN, NEW JERSEY, A CORPORATION OF NEW JERSEY.

PILE-HAMMER.

1,093,210.

Specification of Letters Patent. Patented Apr. 14, 1914.

Application filed August 19, 1913. Serial No. 735,584.

To all whom it may concern:

Be it known that I, MAX SCHALSCHA, a citizen of the United States, residing at Summit, in the county of Union and State 5 of New Jersey, have invented a certain new and useful Improvement in Pile-Hammers, of which the following is a specification.

The invention relates to hammers in which the blows upon the pile are delivered by a 10 rapidly reciprocated ram-head, and more particularly to the connection of the valve-operating rod to such head.

It has been found in practice that the vibration due to the impact of the head upon 15 the pile loosens the valve-rod when the latter is attached by ordinary means, the loosening tendency being materially increased by the lateral strains on the connection caused by swinging movements of the rod 20 and head relatively to each other when the hammer is in operation. Such movements are slight but sufficient, with the vibrations due to shock, to increase greatly the mechanical difficulties involved in maintaining 25 reliable fastening.

The object of the invention is to provide simple but efficient means for reliably securing the valve-rod to the ram-head, and the invention consists in certain details of construction by which the above object is attained, to be hereinafter described and pointed out in the claim.

The accompanying drawings form a part of this specification and show the invention as it has been carried out successfully in practice.

Figure 1 is a vertical section through a hammer equipped with the invention, and partly in elevation. Fig. 2 is a corresponding elevation of the ram-head and valve-rod alone, on a larger scale. Fig. 3 is a vertical section, partly in elevation, corresponding to Fig. 2, the plane of section being indicated by the line 3-3 in the latter figure. Fig. 4 is a horizontal section on the line 4-4 in Fig. 2. Fig. 5 is a face view of the lower end of the valve-rod alone, on a still larger scale. Fig. 6 is a corresponding edge or side view. Fig. 7 is a transverse section on the line 7-7 in Fig. 5.

Similar letters of reference indicate the same parts in all the figures.

A is the body of the hammer, having a cylinder A¹ formed therein in which is a piston B on a vertical piston-rod B¹ reciprocated as usual by steam or compressed air admitted and exhausted alternately from each end of the cylinder by the movement of a rotary valve, not shown, operated by the oscillations of a valve-stem C actuated by the valve rocking levers C¹ C². The latter are moved by cams or projections D¹ D² on a vertical valve-rod D carried by the ram-head B² on the lower end of the piston-rod B¹ and reciprocating therewith in the usual manner.

The strains tending to loosen the valve-rod D from the ram-head B² are very strong and are resisted by forming a vertical dovetailed recess in the face of the head in which is received the corresponding dovetail-shaped lower end D³ of the valve-rod, matching snugly in the recess and held by bolts F F extending through the valve-rod and head. Thus attached the longitudinal strains due to the sudden rapidly repeated shocks of the ram, tending to lift the rod from the head are resisted by the bolts F F, and the outward lateral loosening strains due to the pendulous or swinging movements of the valve-rod and head relatively to each other are resisted by the dovetail form of the rod and recess. After the nuts F¹ F¹ have been firmly tightened the protruding ends of the bolts are preferably slightly spread or upset by a center-punch or otherwise to prevent backing off and consequent loosening.

By seating the dovetailed end of the rod in the correspondingly dovetailed recess in the ram-head, and securing it by the transverse bolts, the outward strains on the latter are successfully resisted and the connection reliably maintained.

Such parts of the hammer as are not specifically described may be understood to be of the ordinary or any approved types.

I claim:

In a hammer of the character set forth, a reciprocating ram-head having a dovetailed recess in its face, a valve-rod carry-

ing at one end means for operating the valve of such hammer, and dovetailed at the opposite end to match to and fit closely in such recess, and bolts extending through said dovetailed lower end into said ram-head.

In testimony that I claim the invention

above set forth I affix my signature, in presence of two witnesses.

MAX SCHALSCHA.

Witnesses:

CHARLES R. SEARLE,

CORA M. FREDERICKS.
